UNITED STATES PATENT OFFICE.

MAXMILLIAN ERNST, OF CLEVELAND, OHIO.

DESIGN FOR A BADGE.

SPECIFICATION forming part of Design No. 24,319, dated May 21, 1895.

Application filed March 23, 1895. Serial No. 542,988. Term of patent 3½ years.

To all whom it may concern:

Be it known that I, MAXMILLIAN ERNST, a citizen of the United States of America, residing at Cleveland, in the county of Cuyahoga and State of Ohio, have invented and produced a new and original Design for Badges, of which the following is a specification, reference being had to the accompanying drawing, forming a part thereof.

10 The drawing shows a face view of a badge embodying my design.

My design consists in such a configuration as to represent a bird, a, holding a bell, b, suspended from its bill, and a flag c unfurled at the side of the bird. 15

What I claim is—

The design for a badge, herein shown and described.

In testimony whereof I sign this specification, in the presence of two witnesses, this 14th 2c day of March, 1895.

MAXMILLIAN ERNST.
